INVENTOR
Herman G. Pape.

UNITED STATES PATENT OFFICE.

HERMAN G. PAPE, OF NEW YORK, N. Y.

MOUTHPIECE.

1,419,513.

Specification of Letters Patent. Patented June 13, 1922.

Application filed September 11, 1919. Serial No. 323,125.

To all whom it may concern:

Be it known that I, HERMAN G. PAPE, a citizen of the United States, and resident of New York, in the county of New York and State of New York, have invented certain new and useful Improvements for Mouthpieces, of which the following is a specification.

This invention relates to improvements in mouthpieces for sound transmitting and analogous appliances.

The objects of this invention are natural and undistorted wave transmission, maximum results of efficiency, privacy, hygiene, advertising, and simplicity of manufacture.

By an examination of the accompanying drawing in connection with the following specification, it will be readily seen, that the various features described contribute to the general and combined objects aforesaid.

Figure 1 is a side elevational view of a transmitter and allied parts made in accordance with the invention.

Figure 2 is a partial longitudinal sectional and elevational view of the same, drawn to an enlarged scale.

Figure 3 is a fragmentary sectional view showing a modification in construction.

Figure 4 is a front elevational view of the mouthpiece and disc.

Figure 5 is a fragmentary plan view of the disc in detail.

The mouthpiece 2 is fastened by screw threads at its base into the casing 1. The wall of this portion of the mouthpiece is provided between its threads or exterior surface, and its interior or sound concentrating surface with an annular exhaust recess or cavity 12 meeting with the exhaust vents 13. Through provision of this recess, the rear sound concentrating portion of the mouthpiece constitutes really an interior wall. This wall is extended beyond the threaded portion and within closest possible proximity to the diaphragm, say within .020" to .025", which makes for most intense concentration of the waves against the diaphragm possible. 14^a indicates the central sound chamber of the instrument, from which the waves are conducted by means of the exhaust vents after having passed through the concentrating chamber of the mouthpiece.

To protect the diaphragm 4 and micro-

phone element 10, I provide a central, preferably spherical insert piece or protector 15 having opposed lateral supports 16 that are rigidly affixed or sprung into the cavities 17. These cavities, as shown in Fig. 3, may be constituted by making direct through passageways of some of the vents 13 from the exterior of the mouthpiece to the interior of the sound concentrating chamber.

The mouthpiece is preferably made of molded material, which when pre-heated after molding, will readily yield sufficiently for the springing into the cavities 17 of the insert piece extensions 16, when, after cooling, it is practically impossible to remove this part again. I do not wish to limit myself to any specific method of affixing or holding the said ball insert piece 15 within the mouthpiece, since numerous other methods may be resorted to.

I prefer the insert piece 15 as fully shown in Figs. 2 and 4 of the drawing rather than the fixed conical guard 15' as shown in Fig. 3 because it is revoluble and will thus permit of ready all around cleaning without the removal of the mouthpiece for that purpose. Thus I have not only constructed a mouthpiece that is webless and of durable and simple construction, but also one that has an extremely low internal resistance to sound waves, and makes possible for finest articulate results by way of the very small outlet at 14 of the main chamber and the very close relation of the part 14 to the diaphragm of the instrument.

Thus the user of this mouthpiece may secure splendid results with the use of but a very mild voice, owing to the features above described, and disturbance or annoyance to others is greatly avoided and greatest possible privacy is the result of the user.

To the rear of the exhaust vents 13 the usual shoulder 19 meets with the transmitter front piece 1. In front of the exhaust vents 13 however, I have provided an extra shoulder 19' that meets with the cupped or saucer shaped privacy or advertising disc 18 that abuts with its rear edge against the transmitter front piece 1 near or at its periphery. Thus, the disc 18 forms a capacity chamber 20 for the waves that are exhausted from the vents 13 of the mouthpiece; besides that it serves as a means for keeping the vents 13 constantly open and unobstructed.

The disc 18 may be made up of any suitable material and in any manner desired. It may contain, besides the service number of the line, any other inscribed or embossed advertising matter. It may be made to constitute a calendar, or any other information may be contained thereon. There always has been real need for such provision or means, free from all service interfering and demoralizing nature. In this direction, the means thus far provided, have, to the best of my knowledge very much failed their purpose.

It will be distinctly noted, that the location of my muffler, its method of use, its close alinement with the transmitter front, its exceedingly shallow construction and rather flat and wide instead of long shape, and its manner of subdued acoustical exhaust after the waves that have entered the funnel from the speaker's mouth have first impinged upon the diaphragm, set forth distinct advancements in the art over previous methods employed and set forth for instance in the patents to Kracker, Woodward, Kintner and Bellows, bearing numbers 901,108; 916,245; 938,060 and 1,248,998 respectively. Not only have I avoided forward extension of the apparatus, but I have really provided a more complete and standard equipment over these devices that were only attachments to present equipment in use.

From the capacity chamber 20 the sound waves are finally emitted through the exhaust vents 21, located in the peripheral portion of the disc 18. These vents are of a number or capacity that is less than that of the vents 13 (or their capacity), located in the mouthpiece, which makes for best muffling of the finally emitted waves and consequent privacy, without the necessary introduction of a lot of chambers within the disc 18 or its formed chamber 20.

In operation: Incoming sound waves, designated by the arrows X X entering the mouthpiece, are concentrated in their passage and caused to pass the protector 15. They then pass through the smallest portion of the concentrating chamber of the mouthpiece at 14 and impinge against the diaphragm 4 of the instrument. The waves, after impinging upon the diaphragm 4 pass around the extension 14 of the mouthpiece and enter the groove or recess 12. After entering the recess 12, they pass through the mouth piece exhaust vents 13 into the capacity or muffling chamber 20 of the disc 18, whence they are emitted in subdued and indistinct manner out of the exhaust vents 21 into the outer air.

I wish therefore to be distinctly understood, that the important instrumentalities, fundamental parts, features of my invention, or their arrangement and organization, may be materially varied without departing from

the fundamental spirit disclosed and will still come within the scope of my claims hereinafter presented.

What I claim as new and desire to secure by Letters Patent of the United States is:—

1. A mouth piece of the concentrator class described, said mouthpiece having a substantially heavy wall and being provided on the exterior of its smaller end with a screw thread, a trumpet shaped main sound passageway, there being a cavity located entirely within the base of said wall between said thread and the main sound passageway concentric therewith and having radial exterior exhaust openings meeting with the cavity.

2. A concentrator mouthpiece comprising a diaphragm, said mouthpiece being provided with a solid and substantially heavy wall having exterior screw threads at its base, said mouthpiece containing a trumpet shaped main sound passageway whose surrounding wall extends within closest possible proximity to the diaphragm of the instrument, in the base of said wall and between said threads and the main sound passageway being a cavity that is met by exterior means of exhaust.

3. A mouth piece of the concentrator class described comprising a constantly convex conical main sound passageway terminating in a single outlet of relatively small diameter, a globular protector rotatably mounted within the same, and radial means of dissipation in co-operative relation with said main sound passageway located entirely at the outlet end.

4. A mouthpiece of the sound concentrator class described comprising an intake end and an outlet end, a constantly convex conical main sound passageway, a globular protector located at the small end of said main sound passageway, radial dissipating means at said small end of said main sound passageway, clear of the walls thereof, said dissipating means being in connection with said main sound passageway, said main sound passageway being whole at its outlet and intake ends and split at a point intermediary of said ends.

5. A mouth piece of the concentrator class described for use with a phonetic instrument comprising a wall, a diaphragm behind said wall, a central sound chamber between said wall and said diaphragm, said mouthpiece having a substantially heavy wall surrounding the main sound passageway, said main sound passageway leading into the central sound chamber, a cavity disposed wholly within the base portion of said wall in substantially parallel relation to the axis of the main sound passageway and connecting with the central sound chamber, and one or more exhaust vents meeting with the cavity.

6. A hollow concave muffler designed for

use with a mouthpiece of the concentrator class described having a means of exhaust at its base portion, said muffler being for location over said means of exhaust.

5 7. A hollow muffler for use around a mouthpiece of the funnel-form described provided with exhaust vents at or near its base or small end, a central opening in said muffler for said mouthpiece, and final exhaust means for said muffler.

10 8. In association with a muffler having a central opening for the reception of a mouthpiece, a mouthpiece provided with special means for the locating or positioning of said muffler, said mouthpiece having one or more exhaust vents located wholly within the body of said muffler, and one or more exhaust vents in communication with the outer air.

15 9. In association with a phonetic instrument comprising a diaphragm, a wall, a central sound chamber between said diaphragm and wall, a hollow muffler closely alining said wall, a mouthpiece fixed to said wall, said muffler having a central opening for said mouthpiece, a main sound passageway through said mouthpiece leading into said central sound chamber, said muffler being substantially for the purpose of muffling exhausted sounds from said central sound chamber after they have passed

20 30 through the main sound passageway of said mouthpiece into said central sound chamber.

10. In association with a mouthpiece of the funnel-form described, a wall of a phonetic instrument, a diaphragm within said instrument, a central sound chamber between said wall and diaphragm, a perforated shal-

low disc of cup-shaped construction forming a muffler with said wall, a central opening for the reception of said mouthpiece, and means for conducting deflected sound waves from the central sound chamber.

11. A mouthpiece of the sound concentrator class described comprising an intake and an outlet end, and having a main webless bore or passageway of constantly tapering formation, a substantially heavy wall surrounding the main bore having a conical exterior, mounting means at the exterior of said outlet end, exhaust vents located wholly within the wall of said outlet end, the exhaust vents being in co-operative relation with the air on the exterior of said mouthpiece through the main bore, the bore being whole at said intake end and said outlet end and split in two between said ends.

12. A concentrator mouthpiece of the class described, said mouthpiece having a substantially heavy wall and being provided with a fastening means on its exterior for engaging with another device, a trumpet shaped main sound passageway, there being a cavity located entirely within the base of said wall between the fastening means and the main sound passageway, and having a radial exterior exhaust opening meeting with the cavity.

Signed at New York, in the county of New York and State of New York this 9th day of September, A. D. 1919.
